UNITED STATES PATENT OFFICE.

SENZO OYAMA, OF HILO, TERRITORY OF HAWAII.

PASTEURIZING APPARATUS.

Application filed November 4, 1926. Serial No. 146,227.

This invention relates to an apparatus for the Pasteurization of bottled milk.

An object of the invention is the provision of a process for Pasteurizing bottled milk and in which the filled bottles are cooled for approximately five minutes by passing the same under a cooling liquid and then removing the bottles under a spray of hot liquid and retaining the bottles at approximately 180° temperature for thirty minutes. At the end of such time the bottles are then conveyed under a cooling spray and retained there for approximately fifteen minutes, after which the bottles may be removed by an endless conveyor.

A further object of the invention is the provision of a device for Pasteurizing bottled milk and in which the bottles are slowly conveyed through a closed chamber having reservoirs at its upper end provided with spraying means adapted to be automatically operated as the bottles pass beneath the various types of spraying means.

A still further object of the invention is the provision of a Pasteurizing device in which heating and chilling compartments are provided through which a container is adapted to travel carrying a plurality of bottles, the container being adapted to actuate the valves to open position for causing the spraying of the bottles with either cold or hot water, the hot and cold water being carried in respective reservoirs at the top of the device and collected by reservoirs at the bottom, a pump being employed for forcing the water from the lower containers to the upper containers and directly over the path of travel of the container for the bottled milk.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a side view in elevation of a Pasteurizing device constructed in accordance with the principles of my invention.

Figure 2 is a plan view of the same.

Figure 3 is a longitudinal sectional view of the device.

Figure 4 is an enlarged detail of an automatic actuating device for the valves which control the circulation of the water.

Figure 5 is an end view of the valve controlling device shown in Figure 4.

Figure 6 is an end view of the Pasteurizing device.

Figure 7 is a fragmentary view in perspective of the container for housing the bottled milk during Pasteurization.

Referring more particularly to the drawings, 10 designates a cabinet formed of steel which is closed at its opposite ends by a pair of doors 11 held against movement by means of latches 12. Below the doors are provided transverse openings 13 through which is adapted to travel a section of a continuous carrier 14. The carrier is supported at one end by an idling sprocket 15 and is driven by sprockets 16. These sprockets are carried by a shaft 17 driven by a gear 18. The gear 18 meshes with a gear 19 driven by a shaft 20 which in turn is driven by a worm gear 21. A worm 22 on a shaft 23 meshes with worm gear 21. Shaft 23 is driven by a worm gear 24 which is in mesh with a worm 25. Worm 25 is driven by a gear 26 meshing with a gear 27 on the main driving shaft 28. This shaft carries at one end a gear 29 meshing with the gear 30 on a motor shaft 31 driven by an electric motor 32. The motor through the shaft 28 is adapted to drive a pair of pumps 33 and 34.

The cabinet 10 is provided with a chamber 35 disposed between reservoirs located at different horizontal levels or respectively at the top and bottom of said cabinet. A reservoir 36 is disposed upon the top of the cabinet and is adapted to provide a receptacle for water and is heated by means of a series of coils of pipe 37 disposed therein. These pipes are connected in any approved manner with a source of live steam so that the water in the reservoir 36 may be maintained at approximately 180° F. A second reservoir 38 is located above the chamber 35 and is adapted to be cooled by means of coils 39 located within the reservoirs. These coils are connected with a suitable source of refrigerant for maintaining water in the reservoir 38 at approximately 60° F.

Adjacent the bottom of the cabinet a tank

is placed which is divided into three reservoirs 39, 40 and 41 by partitions 42. Reservoirs 39 and 41 are connected together by a pipe 50 controlled by a valve 50^a.

5 In the chamber 35 are located a plurality of nozzles 46 connected to a pipe 47 which in turn is in communication with the bottom of the reservoir 36 which contains the hot water. A plurality of nozzles 48 connected with a pipe 49 are also located in the chamber 35. The pipe 49 is in open communication with the bottom of the reservoir 38 and in which the cold water is retained. Thus it will be seen that cold water is 15 sprayed downwardly and which is collected by reservoirs 39 and 41. A drain 51 is connected with reservoir 40 so that the water from said reservoir flows directly to reservoir 100 while water from reservoirs 39 and 20 41 drains directly into a reservoir 101 by means of a pipe 52. Reservoirs 100 and 101 are separated by an air channel 102.

A container 53 having its opposite ends open and adapted to be closed by doors 54 25 is placed upon the travelling conveyor 14 and moved slowly through the cabinet 10. This container has a perforated top 55 whereby either hot or cold water may percolate through the openings and be discharged upon the bottled milk located on the trays 56. These trays are supported at their edges by means of angle arms 57 secured to the side walls of the container.

Secured to the top 55 of the container are 35 cleats 58 which extend outwardly of said container and in longitudinal alinement with a vertical plane passing through the center of the casing. A tracks 60 U-shape in cross section has a downwardly curved portion 61 adapted to be engaged by rollers 62 carried 40 at one end of a curved arm 63 pivotally mounted at 64 on a U-shaped bracket 65 which is carried by the top wall of the chamber 35. On the end of the curved arm 63 45 which is opposite to that carrying the roller 62 is formed a valve 66 which engages the open free end of the nozzles 48 and the roller 62 is of sufficient weight to maintain the nozzle closed and prevent escape of water 50 from the tank 36 until operated by the track 60.

The nozzles 46 are also provided with 55 valves 67 carried at the free ends of levers or curved arms 68 which are pivoted at 69 on the brackets 70 supported from the top wall 35^a of the chamber 35. A pipe 71 is connected with the pump 33 and is adapted to withdraw water from reservoir 101 and force said water into chamber 38. The upper end of the pipe is connected to a lateral extension 72 of the chamber 38. The water 65 from reservoir 100 is forced upwardly through pump 34 through pipe 73 which has its upper end connected with an extension of reservoir 36. By this means the hot water

in reservoirs 36 and 100 is maintained in constant circulation while the cold water in reservoirs 39, 41 and 38 are also kept in constant circulation by the pump 33. The pump 33 is connected with reservoir 101 while 70 pump 34 is connected with reservoir 100. From an inspection of Figure 3 it will be noted that chambers 36 and 38 are separated by an air space 74.

It will be noted from Figure 5 that the 75 nozzles 48 are grouped in pairs with a plurality of cups 66 forming the closures for sealing the nozzles. The ends of levers 63 near the roller 62 are bifurcated to receive the roller upon an axle 78.

The operation of my device is as follows:

The bottled milk which is to be Pasteurized is placed upon the trays 56 within the container 53 and the container is then placed upon the travelling carrier 14, the doors 11 having been opened to permit the container being carried within the chamber 35. The motor 32 is then started and the carrier slowly conveys the container within the chamber 35 and as it passes beneath the nozzle 43 the valve 45 is opened to permit cold water being sprayed upon the perforated top 55 through which the water percolates and comes in contact with the bottles on the trays 56.

As the container is moved forwardly beyond the nozzle 43 the first wheel 62 carried by the arm 68 engages the curved portion 61 of the track 60 and rides upwardly until it reaches the horizontal portion of the track. As the wheel rides upwardly on the curved portion 61 the arm or lever 68 is being rocked and moving the valve 67 away from the nozzles 66, permitting water to escape through the nozzles from tank 36 which carries the hot water, thereby causing the bottles to be sprayed. As the container still continues its inward journey the next succeeding roller 62 is engaged by the track thereby releasing the valve 67 from the second nozzle 46 thereby permitting further hot water to be sprayed upon the perforated top 65 whence the water passes over the bottles. The third wheel 62^a is also engaged by the track 60 opening the valve engaging the nozzles 46 and spraying further hot water upon the bottles.

When the track 60 reaches the last two rollers 62 their respective arms 63 are oscillated releasing the water from the nozzles 48 which is sprayed downwardly upon the bottles and suddenly chilling the same and their contents.

The length of the chamber 35 considered in connection with the speed of the travelling carrier 14 is such that it will require five minutes for the bottles to pass beneath the nozzle 43, thirty minutes to pass below the nozzles 36, and fifteen minutes to pass beneath the nozzles 48. By this process the 130

contents of the bottles will be heated gradually to about 180° F. and then maintained at that temperature for approximately thirty minutes. After this the contents of the bottles are gradually cooled to about 60° and then conveyed into packages for shipment.

The doors 11 are closed after the container 53 has entered the same and are adapted to open as the container is ready to pass through the opposite end of the chamber 35.

It will be noted from an inspection of Fig. 6 that the reservoirs 39 to 41, inclusive, are arranged longitudinally of the device and at one side of the operating mechanism for the traveling carrier 14. A spout 120 is connected to the container 53 and is adapted to project through the lower open end of the chamber 35 so that all water whether hot or cold which is sprayed through the perforated top 55 into the container 53 may be discharged through the spout 120 adjacent the closed bottom 121 of the container, the spout directing the warm or cold water into the various reservoirs 39 to 41, inclusive. The reservoirs are so arranged that the reservoir 39 will receive the cool water from the nozzle 43 while tank 40 will receive the hot water which has been discharged from the nozzles 46. The reservoir 41 will receive the cool water from reservoir 38 after it has sprayed down through the chamber 53. The pump 33 is adapted to return the water from tank 101 to tank 38 while pump 34 returns the water from tank 100 to tank 36. An outlet pipe 122 connected with tank 100 is adapted to drain the tank when necessary. A valve 124 in the pipe 125 controls the draining of the water from tank 100.

Cool water is sprayed from the nozzle 43 onto the bottles in the container as said container enters the sterilizing chamber 35. Due to the fact that milk after being handled during bottling or during conveyance of the milk to the container 53 will be heated to substantially the temperature of the atmosphere which would tend to cause bacteria in the milk to cultivate. The milk is preferably then passed under a cooling agent from the nozzle 43 and thoroughly cooled to check the growth of any bacteria before it is passed under the first heating medium. Otherwise, if the milk were passed under the heating fluid the initial heating would be sufficient to increase the bacterial growth of the milk which is undesirable.

What I claim is:

1. A Pasteurizing device comprising a cabinet, a travelling carrier movable through the cabinet, a plurality of reservoirs located below the travelling carrier, a pair of reservoirs at the top of the cabinet and means for releasing the water from the re-

servoirs at the top of the cabinet for spraying, a container for carrying bottled liquid adapted to be drawn through the chamber by the travelling carrier and sprayed by liquids of different temperatures which are contained within the reservoirs at the top of the cabinet, nozzles connected with the reservoirs at the top of the chamber, means co-acting with the ends of the nozzles for maintaining the nozzles closed, and means mounted on the top of the movable container for actuating the closing means of the nozzles to open position.

2. A device for Pasteurizing milk comprising a cabinet having reservoirs at its top for receiving respectively hot and cold water, reservoirs at the bottom of the cabinet and adapted to receive the hot and cold water released from the upper reservoirs, said cabinet having a chamber located between the upper and lower reservoirs, a travelling carrier movable through the chamber and adapted to transport bottled liquids through the chamber, nozzles connected with the reservoirs at the top of the cabinet, means co-acting with the ends of the nozzles for closing the nozzles, and means mounted on the top of the travelling carrier adapted to release the closing means to permit liquids to be sprayed upon the bottled liquids passing through the chamber, the liquids discharged from the nozzle being adapted to drain into the reservoirs at the bottom of the cabinet.

3. A device for Pasteurizing milk comprising a cabinet having reservoirs at its top for receiving respectively hot and cold water, reservoirs at the bottom of the cabinet and adapted to receive the hot and cold water released from the upper reservoirs, said cabinet having a chamber located between the upper and lower reservoirs, a travelling carrier movable through the chamber and adapted to transport bottled liquids through the chamber, nozzles connected with the reservoirs at the top of the cabinet, means co-acting with the ends of the nozzles for closing the nozzles, and means mounted on the top of the travelling carrier adapted to release the closing means to permit liquids to be sprayed upon the bottled liquids passing through the chamber, the liquids discharged from the nozzle being adapted to drain into the reservoirs at the bottom of the cabinet, and means for forcing the liquid from the lower reservoirs to the upper reservoirs.

4. A device for Pasteurizing milk comprising a cabinet having reservoirs at its top for receiving respectively hot and cold water, reservoirs at the bottom of the cabinet and adapted to receive the hot and cold water released from the upper reservoirs, said cabinet having a chamber located between the upper and lower reservoirs.

voirs, a travelling carrier movable through the chamber and adapted to transport bottled liquids through the chamber, nozzles connected with the reservoirs at the top of the cabinet, means co-acting with the ends of the nozzles for closing the nozzles, and a track mounted on the top of the travelling carrier adapted to engage the closing means for moving the closing means away from the nozzles to permit liquids to be sprayed upon the bottled liquids passing through the chamber, the liquids discharged from the nozzle being adapted to drain into the reservoirs at the bottom of the cabinet, means for forcing the liquid from the lower reservoirs to the upper reservoirs, means for cooling the liquid in one of the upper reservoirs, and means for heating the liquid in the other reservoir.

20 5. A device for Pasteurizing liquids comprising a cabinet having a pair of reservoirs at its upper end, a plurality of reservoirs at its lower end, said cabinet having a chamber between the reservoirs, a travelling carrier adapted to move through the chamber, a plurality of nozzles in open communication with the containers at the top of the cabinet and disposed within the chamber, arms pivotally mounted on the top of the cabinet and having valves engaging the nozzles for closing the same, rollers carried at the opposite ends of the arms and of sufficient weight to maintain the valves in sealed engagement with the nozzles, a container adapted to carry a plurality of bottles disposed on the travelling carrier, and means engageable with the rollers and oscillating the arms to release the valves from the nozzles.

40 6. A device for Pasteurizing liquids comprising a cabinet having a pair of reservoirs at its upper end, a plurality of reservoirs at its lower end, said cabinet having a chamber between the reservoirs, a travelling carrier adapted to move through the chamber, a plurality of nozzles in open communication with the containers at the top of the cabinet and disposed within the chamber, arms pivotally mounted on the top of the cabinet and having valves engaging the nozzles for closing the same; rollers carried at the opposite ends of the arms and of sufficient weight to maintain the valves in sealed engagement with the nozzles, a container adapted to carry a plurality of bottles disposed on the travelling carrier, and tracks mounted on top of the container and engaging the rollers for oscillating the arms and releasing the valves from the nozzles.

60 7. A device for Pasteurizing liquids comprising a cabinet having a pair of reservoirs at its upper end, a plurality of reservoirs

at its lower end, said cabinet having a chamber between the reservoirs, a travelling carrier adapted to move through the chamber, a plurality of nozzles in open communication with the containers at the top of the cabinet and disposed within the chamber, arms pivotally mounted on the top of the cabinet and having valves engaging the nozzles for closing the same, rollers carried at the opposite ends of the arms and of sufficient weight to maintain the valves in sealed engagement with the nozzles, a container adapted to carry a plurality of bottles disposed on the travelling carrier, tracks mounted on top of the container and engaging the rollers for oscillating the arms and releasing the valves from the nozzles, a nozzle located adjacent one end of a container and connected with a source of cold water for spraying the bottled liquids in the container when the container enters the chamber.

8. A device for Pasteurizing liquids comprising a cabinet having a pair of reservoirs at its upper end, a plurality of reservoirs at its lower end, said cabinet having a chamber between the reservoirs, a travelling carrier adapted to move through the chamber, a plurality of nozzles in open communication with the containers at the top of the cabinet and disposed within the chamber, arms pivotally mounted on the top of the cabinet and having valves engaging the nozzles for closing the same, rollers carried at the opposite ends of the arms and of sufficient weight to maintain the valves in sealed engagement with the nozzles, a container adapted to carry a plurality of bottles disposed on the travelling carrier, tracks mounted on top of the container and engaging the rollers for oscillating the arms and releasing the valves from the nozzles, a pump connected with the lower reservoir, and a conduit connecting a pump with an upper reservoir for returning the water from the lower reservoirs to the upper reservoirs.

9. A device for Pasteurizing bottled liquids comprising a cabinet having a chamber therein, a travelling carrier movable through said chamber, a container for carrying bottled liquids and comprising a housing closed at all sides and open at its bottom, said housing having a perforated top, cleats projecting from the opposite ends of the perforated top and disposed in longitudinal alignment with the vertical plane passing through the center of the casing, a track having an intermediate horizontal portion with the ends curved and bent downwardly and secured to the free ends of the cleats.

SENZO OYAMA.
